UNITED STATES PATENT OFFICE.

EDWARD P. HATCH, OF LAGRANGE, ILLINOIS.

NEEDLE-ACTUATING MECHANISM FOR SEWING-MACHINES.

SPECIFICATION forming part of Letters Patent No. 717,848, dated January 6, 1903.

Application filed February 24, 1902. Serial No. 95,279. (No model.)

To all whom it may concern:

Be it known that I, EDWARD P. HATCH, a citizen of the United States, residing at La-
5 grange, in the county of Cook and State of Illinois, have invented a new and useful Im-
provement in Needle-Actuating Mechanism for Sewing-Machines, of which the following
is a specification.

My object is to provide a sewing-machine
10 with mechanism of an improved construction
to adapt the machine for use in such work as
the stitching of wide trimming on corsets.
In this class of work the ordinary machine
cannot be used to advantage because of the
15 necessity of stopping the machine and lifting
the presser-foot whenever the impenetrable
steels, whalebones, or the like pass across
the throat-plate.

My object is to provide a sewing-machine
20 with mechanism which will operate auto-
matically to cause material interposed in the
work and which is too hard or too thick to be
penetrated and stitched or to be readily pene-
trated and stitched as without danger to the
25 needle to be fed across the path of the needle
intermediate of the rise and descent thereof.
While the desired result may be accomplished
in a different way, as by accelerating the feed
of the work at the proper times to carry such
30 hard material across the path of the needle be-
tween the regular strokes of the latter, I pre-
fer to carry out my invention by providing
mechanism operating to arrest reciprocation
of the needle-bar while a thickness of mate-
35 rial impenetrable by the needle is being fed
beneath the presser-foot and automatically
throw the needle-bar into operation again
when the said material has passed.

While my invention is more especially
40 adapted for use in stitching lace, ribbon, or
the like on corsets, it is not to be limited to
this particular use, as it may be found ad-
vantageous in other classes of work.

My invention in its broadest sense consists
45 of means for automatically rendering the
penetrating device of a sewing-machine in-
active at the impenetrable portions of the
work.

In carrying out my invention according to
50 the preferred construction I employ a tri-
pping device resting at one end in contact with
the work or material being stitched and ac-

tuated thereby to release engagement be-
tween the needle-bar and its actuating cross-
head when the material fed into line with the 55
needle is too thick or so hard as to endanger
the needle and to bring about reengagement
between the needle-bar and its cross-head
when the material passing into line with the
needle is of a nature to be or intended to be 60
stitched.

Referring to the drawings, Figure 1 is a
front view of so much of a sewing-machine as
is necessary to illustrate the operation of my
improvements; Fig. 2, a broken side elevation 65
thereof; Fig. 3, a broken top plan view; Fig. 4,
an enlarged broken view, partly sectional, of
the side opposite that shown in Fig. 2; Fig. 5,
an enlarged view similar to the lower part of
Fig. 1, but showing a presser-stem in addi-
70 tion to the auxiliary presser-foot; Figs. 6 and
7, plan sections taken on lines 6 and 7 in Fig.
4; Fig. 8, a plan section taken on line 8 in
Fig. 5; Fig. 9, a broken section taken on line
9 in Fig. 8; Fig. 10, a perspective view of 75
details at the upper end of the mechanism
at the upper guide for the needle-bar and
presser-bar; Fig. 11, a perspective view of a
lever and serrated wheel forming one of the
details of my improvements, and Fig. 12 a 80
plan view of a throat-plate adapted for use
with my improvements.

A is the arm of a sewing-machine, carrying
the upper guide-head A' and the lower guide-
head A². 85

B is the needle-bar lever, connected by a
link B' with a reciprocator or cross-head B².

C is a needle-holder or needle-bar recip-
rocating through guide-openings in the heads
A' A², and D a presser-bar, also reciprocating 90
through guide-openings in said heads. On
the lower end of the presser-bar D is a
presser-foot D', and the presser bar and foot
are held down by the presser-spring D².

The parts described are common to sewing- 95
machines of the type shown. The cross-head
B² reciprocates the needle-bar; but in the pres-
ent construction the needle-bar is not rigidly
secured to the cross-head. In the needle-
bar in the position shown is a notch a. Ful-
crumed upon a pin b' in a horizontal recess b
in the cross-head B² is a bell-crank lever E,
having a notch-engaging arm, clutch, or dog
c and an outward-extending arm c', against 100

which bears a spring c^3 , fastened against the cross-head and operating normally to press the arm or dog c against the needle-bar to engage the notch a . Sliding in a guide-opening in the lower head A^2 and through a guide-opening d in the upper guide-head A' is a tripping-bar F , provided along its upper end portion with a feather d' , movable in a groove d^2 at the side of the opening d to prevent axial turning of the bar F . On the lower end of the bar F is a head F' , to which is pivoted one end of a tripping-lever F^2 , which is fulcrumed between its ends upon a pin e , having bearings in ears e' on the presser-foot D' . At its opposite or free end the lever F^2 carries a toothed wheel F^3 , journaled upon a pin e^2 , extending through the lever. On the rod F is an ear f , and connected therewith at one end and with an ear f' on the head A' is a spring F^4 , which tends normally to draw the rod F in the upward direction and raise the rear end of the lever F^2 to press the forward end thereof and wheel F^3 in the downward direction. The downward movement of the toothed wheel F^3 is limited by engagement of the free end portion of the lever F^2 with a recessed portion e^3 of the presser-foot. On the presser-bar D in the position shown is a collar D^3 , which carries a pin or screw D^4 , upon which the presser-spring D^2 bears. Integral with the collar D^3 is a horizontal laterally-extending sleeve portion D^5 , having an opening g along one end portion. Mounted in the sleeve D^5 is a rock-shaft G , provided at the opening g with a laterally-projecting lug or finger G' . On the outer end of the rock-shaft G is a collar G^2 , carrying a downward-projecting cam-finger G^3 . The lug or finger G' engages a short vertical slot h in the bar F . The cross-head B^2 is formed on one side with a cam-surface B^3 , terminating just above the lever E . In the upper part of the needle-bar C is a socket i , and fastened against the upper surface of the head A' is a spring-catch i' , secured in place by means of a screw i^2 . The spring-catch i' bears gently against a flattened surface i^3 of the needle-bar in the reciprocation thereof, and in the movement of the needle-bar to the highest point in its reciprocation the catch engages gently with the socket i .

When the free end of the lever F^2 is down or in the position shown by full lines in Fig. 5, the rod F is in its raised position, whereby the rock-shaft G and cam-finger G^3 are in the position shown by full lines in the figures. Raising of the free end portion of the lever F^2 draws the rod F in the downward direction, causing the rock-shaft on account of the engagement of the lug G' with the slot h of the bar F to turn and swing the finger G^3 from the position shown by full lines to that shown by dotted lines in Fig. 4, whereby it is in the path of the cam-surface B^3 of the cross-head. When the finger G^3 is in this position, the cam-surface B^3 in the rise of the cross-head B^2 and needle-bar slides upward

along the finger G^3 until the latter engages the arm c' of the lever E and swings it against the resistance of the spring c^3 to disengage the arm or dog c from the notch a of the needle-bar. This unlocking or release of the needle-bar from the cross-head takes place just before the needle-bar reaches the highest limit of its movement, and at this time the engagement of the catch i' with the notch i of the needle-bar holds the latter steadily while the cross-head is sliding up and down thereon.

In operation when the presser-foot is lowered and presses upon the material to be stitched the toothed wheel F^3 projects below the presser-foot and rests upon and may penetrate said material. I prefer to provide a throat-plate H , as shown in Fig. 12, which is cut away at H' , as shown, so that the teeth of the wheel will not ride upon the surface of the plate. In stitching corsets in the direction across the steels, whalebones, or the like when a steel, whalebone, or similar hard surface passes beneath the presser-foot it engages the tripping-wheel F^3 , and as the teeth of the wheel cannot penetrate said material the wheel and that end of the lever F^2 are raised to lower the bar F , turn the rock-shaft G , and swing the arm G^3 into the path of the lever E , whereby in the following upstroke of the needle-bar it is unlocked or released from engagement with the cross-head and held in the elevated position by the catch-spring i' . While the hard material is passing beneath the wheel F^3 the cross-head in its reciprocation will slide up and down upon the needle-bar without lowering the needle and no stitching will be performed. When the hard material has passed from beneath the roller F^3 , and therefore passed the line of reciprocation of the needle, the toothed roller under the resilient action of the spring G^3 penetrates the material, causing the adjacent end of the lever F^2 to lower and raise the bar F to swing the finger G^3 out of engagement with the lever E , whereby the dog c in the next rise of the cross-head engages the notch i of the needle-bar and locks it to the cross-head, whereby they reciprocate together and the stitching proceeds.

In stitching several thicknesses of material, as in corsets, it is desirable to provide an auxiliary presser-foot, such as the presser-foot I . It consists of a bar of the shape shown to extend downward through an opening in the main presser-foot D' and engage the material being stitched close to the path of the needle. It is necessary in operation that the auxiliary presser-foot shall release the material when the needle is raised and the material is to be fed along. For this purpose the auxiliary presser-foot is mounted upon a bar I' , which reciprocates through guide-openings in the stationary heads $A^2 A'$. Confined between a collar I^2 on the bar I and the under side of the head A^2 is a spring I^3 , which tends normally to press the auxiliary presser-foot I down

upon the goods being stitched. On the bar I', above the head A², is a collar I⁴, presenting a shoulder in the path of the cross-head B². As the cross-head rises and withdraws the needle from the material being stitched the cross-head strikes the under side of the shoulder I⁴ and raises it, the bar I, and the auxiliary presser-foot, whereby the latter releases the material and permits it to be fed.

10 In conjunction with the auxiliary presser-foot I, I provide an additional presser-foot or presser-stem K, which is attached to the bar I' at one side of the foot I and extends through an opening in the main presser-foot D', close to the side of the wheel F³. The presser-stem K presses upon the material being stitched over the opening H' in the throat-plate and by pressing down said material aids or accentuates the action of the wheel F³, 15 particularly where the steels or the like are close together, and the cloth stretched between them tends to hold the wheel up against the resistance of the spring F⁴.

Although I prefer to provide the tripping-lever F² with a serrated wheel F³ to penetrate fabric to be stitched, the wheel need not necessarily be toothed, nor is it necessary that it shall be a wheel; but it may be a foot-piece of any kind that will slide upon the work. 20 As in stitching corsets the hard steels or bones will increase the thickness of the corset material, such thickness will raise the end of the tripping-lever and actuate the tripping mechanism to release the needle-bar before the 25 hard material passes into line with the needle.

My invention may be applied in stitching any articles where it is desired that the unevenness in the surface shall effect engagement and release between the needle and its 30 reciprocating mechanism or otherwise prevent the needle from stitching for the reasons set forth.

While I prefer to construct my improvements throughout as shown and described, 35 they may be variously modified in the matter of details of construction without departing from the spirit of my invention as defined by the claims.

What I claim as new, and desire to secure 40 by Letters Patent, is—

1. In a sewing-machine, stitch-forming mechanism including a penetrating device and feeding mechanism, and means for automatically rendering the device inactive at the 45 impenetrable portions of the work.

2. In a sewing-machine, stitch-forming mechanism including a needle and feeding mechanism, and means for automatically arresting the action of the needle when the feeding 50 mechanism presents impenetrable portions of the work.

3. In a sewing-machine, stitch-forming mechanism including a needle and feeding mechanism, and means for arresting the action of the needle-bar said means being controlled by surface variations of the work. 55

4. In a sewing-machine, stitch-forming mechanism including a needle-bar and feeding mechanism, mechanism for reciprocating said needle-bar and means for automatically 60 coupling and uncoupling said needle-bar and reciprocating mechanism controlled by surface variations of the work. 70

5. In a sewing-machine, stitch-forming mechanism including a needle-bar and feeding mechanism, mechanism for reciprocating said needle-bar and means including a trip to bear upon the work for uncoupling and coupling the needle-bar and reciprocating mechanism the movements of the trip being 80 effected by variations in the work-surface. 75

6. In a sewing-machine, stitch-forming mechanism including a needle-bar and feeding mechanism, mechanism for reciprocating said needle-bar, means for coupling and uncoupling said needle-bar and reciprocating mechanism and a yielding trip operatively connected with said means and arranged to bear upon the work adjacent to the path of the needle. 85

7. In a sewing-machine, the combination with stitch-forming mechanism including a needle-holder and its reciprocator and feeding mechanism, of engaging and releasing means between the said holder and reciprocator, and actuating means therefor comprising yielding tripping mechanism bearing 90 upon the work. 95

8. In a sewing-machine, the combination with stitch-forming mechanism including a needle-holder and its reciprocator and feeding mechanism, of engaging and releasing means between the said needle-holder and reciprocator, and actuating means therefor comprising yielding tripping mechanism having a wheel engaging the work adjacent to the path of the needle. 100 105

9. In a sewing-machine, the combination with stitch-forming mechanism including a needle-holder and its reciprocator and feeding mechanism, of engaging and releasing means between the said needle-holder and reciprocator, and actuating means therefor comprising yielding tripping mechanism having a toothed wheel engaging and penetrating 110 the work adjacent to the path of the needle. 115

10. In a sewing-machine, the combination with stitch-forming mechanism including a needle-holder and its reciprocator and feeding mechanism, of engaging and releasing means between the said needle-holder and reciprocator, and actuating means therefor comprising a yielding tripping-bar and a tripping-lever connected with said bar and bearing 120 upon the work. 125

11. In a sewing-machine, the combination with stitch-forming mechanism including a presser-foot, needle-holder and its reciprocator and feeding mechanism, of engaging and releasing means between the said needle-holder and reciprocator, and actuating means therefor comprising a tripping-bar and 130

a lever fulcrumed upon the presser-foot connected with said tripping-bar and bearing upon the work.

12. In a sewing-machine, the combination with stitch-forming mechanism including a needle-bar and reciprocating cross-head and feeding mechanism of an engaging and releasing dog upon the cross-head for the needle-bar, and means for actuating said dog comprising yielding tripping mechanism engaging the work.

13. In a sewing-machine, the combination with stitch-forming mechanism including a needle-holder and its reciprocating cross-head and feeding mechanism, of an engaging and releasing dog for the needle-holder upon the cross-head, a dog-operating cam-lever movable into and out of the path of the dog, and actuating means for said cam-lever comprising yielding tripping mechanism bearing upon the work.

14. In a sewing-machine, the combination with stitch-forming mechanism including the needle-reciprocator, feeding mechanism, and presser-foot, of tripping mechanism for throwing the needle into and out of operation, mounted upon the presser-foot and bearing against the work.

15. In a sewing-machine, the combination with stitch-forming mechanism including the needle-reciprocator, feeding mechanism, and presser-foot, of tripping mechanism for throwing the needle into and out of operation, having a lever fulcrumed upon the presser-foot and bearing against the work.

16. In a sewing-machine, the combination with stitch-forming mechanism including the needle-reciprocator, feeding mechanism, and presser-foot, of tripping mechanism for throwing the needle into and out of operation, having a spring-pressed lever fulcrumed upon the presser-foot and a toothed wheel on the lever projecting below the presser-foot and bearing against the work.

17. In a sewing-machine, the combination with stitch-forming mechanism including the needle-reciprocator, feeding mechanism, and presser-foot, of tripping mechanism for throwing the needle into and out of operation, mounted upon the presser-foot and bearing against the work, and a reciprocating auxiliary presser-foot bearing upon the work closely adjacent to the path of the needle.

18. In a sewing-machine, the combination with stitch-forming mechanism including the needle-reciprocator, feeding mechanism, and presser-foot, of tripping mechanism for throwing the needle into and out of operation, having a lever fulcrumed upon the presser-foot and bearing against the work, and a reciprocating auxiliary presser-foot bearing upon the work closely adjacent to said lever.

19. In a sewing-machine, the combination with stitch-forming mechanism including the needle-reciprocator, feeding mechanism, and presser-foot, of tripping mechanism for throwing the needle into and out of operation, having a spring-pressed lever fulcrumed upon the presser-foot and a toothed wheel on the lever projecting below the presser-foot and bearing against the work, and a reciprocating auxiliary presser-foot bearing upon the work closely adjacent to said wheel.

20. In a sewing-machine, the combination with stitch-forming mechanism including the needle-reciprocator, feeding mechanism, and presser-foot, of tripping mechanism for throwing the needle into and out of operation, mounted upon the presser-foot and bearing against the work, and a reciprocating auxiliary presser-foot, bearing upon the work closely adjacent to said tripping mechanism, actuated by the said reciprocator.

21. The combination with a stationary support, needle-bar and its reciprocator and feeding mechanism, of engaging and releasing clutch mechanism between the said needle-bar and reciprocator, a notch in the needle-bar, a catch-spring on said support in the path of said notch when the needle-bar is at the upper limit of its stroke, and actuating means for said clutch mechanism comprising yielding tripping mechanism bearing upon the work.

22. In a sewing-machine, stitch-forming mechanism including a needle-bar and feeding mechanism, means for automatically arresting the action of the needle-bar said means being controlled by surface variations of the work, a presser-foot, and an auxiliary presser-foot arranged closely adjacent to the path of the needle.

EDWARD P. HATCH.
